UNITED STATES PATENT OFFICE.

MARTIN PRIOR BOSS, OF SAN FRANCISCO, CALIFORNIA, ASSIGNOR TO THE HYDRO-CARBON SMELTING COMPANY, A CORPORATION OF WEST VIRGINIA.

METALLURGICAL FURNACE.

SPECIFICATION forming part of Letters Patent No. 732,264, dated June 30, 1903.

Application filed March 12, 1902. Serial No. 97,961. (No model.)

To all whom it may concern:

Be it known that I, MARTIN PRIOR BOSS, a citizen of the United States, residing at San Francisco, county of San Francisco, State of California, have invented certain new and useful Improvements in Metallurgical Furnaces, of which the following is a specification.

My invention relates to a furnace adapted to carry into effect all the metallurgical operations necessary to convert a metal-bearing ore into pig metal.

My invention consists in the construction and arrangement of the chambers in which the metallurgical operations are conducted; also in the construction and arrangement of the chambers in which the air used in the furnace is heated; also to the means employed for feeding the heated air to the oxidizing-chamber; also to the means employed and general arrangement of the apparatus for introducing hydrocarbon fuel into the furnace; also to the various details of construction of the furnace.

The objects sought to be obtained by my invention are: to reduce the first cost of the furnace by consolidating all of the furnaces usually required to conduct the metallurgical operations necessary in a single structure; to reduce the amount of fuel required by utilizing the heat units set free from the ores under treatment—as, for instance, the sulfur in a pyritic ore; to provide means for making use of a hydrocarbon fuel in place of a solid fuel; to provide means for heating the air used in the furnace and for delivering the air into the furnace under pressure; to provide means for moving the ore in the calcining-chamber, and generally to improve the construction of the chambers in which the metallurgical operations are conducted and the furnace as a whole.

The accompanying drawings will serve to illustrate my invention.

Figure 1 is a vertical longitudinal section through the furnace. Fig. 2 is a plan view on the line V V of Fig. 1. Fig. 3 is a plan view on the line W W of Fig. 1. Fig. 4 is a vertical section on the line X X of Fig. 1. Fig. 5 is a vertical section on the line Y Y of Fig.

1. Fig. 6 is a vertical section on the line Z Z of Fig. 1.

Similar numerals and letters indicate like parts.

In the drawings, 5 indicates the body of the furnace. The furnace may be considered as divided into three chambers or sections—*i. e.*, A, the calcining-chamber; B, reducing-chamber; C, oxidizing-chamber. The terms given these chambers serve to indicate generally the metallurgical operations which take place within the respective chambers. Other operations, however, may take place in such chambers.

It will be observed from the drawings that the hearths of the chambers A and B are inclined downwardly toward the hearth of the chamber C, which is horizontal. I do not limit myself in any wise to the angular inclination of the hearths of the chambers A and B, nor do I consider it absolutely essential that the hearth of the chamber C be horizontal, as it may be given an inclination. In practice I consider it preferable to give the hearths of the chambers A and B such an inclination as will produce a forward and downward movement of the ore toward the chamber C.

The hearths of the respective chambers are supported on arches 6. These, however, are not essential, but will be found convenient in practice. The roof of the respective chambers, as shown in the present case, is formed of shaped bricks 7, between which are located pipes 8, adapted to convey water or other cooling fluid. Such a roof I have found to be excellently adapted for use with a furnace such as described. I, however, do not in any wise limit myself to the use of such a roof.

Situated over the roof of the chambers B and C is an air-heating chamber 9. This air-chamber communicates with the atmosphere through an opening 10 and with the chamber 11, under the chamber B, through the flues 12. Located in the forward end of the chamber 11 is a steam or air jet 13, which serves to draw the air through chambers 9 and 11 and discharge it into chamber 14 under chamber C, and thence through the air-passages 15, in the front walls of the chamber C, directly into the chamber. By this means hot air in any amount

may be delivered as required into the chamber C.

Located below a portion of the chamber A is a reciprocating rake 16. The rake is secured to a carriage 17, which moves on a track 18. Forward and backward motion is given to the carriage by means of the chain 19, passing over the pulleys 20, through the link 21. The pulleys receive their motion from any suitable source of power through the pulley 22.

23 indicates hydrocarbon-fuel injectors connected to a source of fuel through a pipe 24. These injectors may be of any suitable construction and have any suitable location in the furnace. In the drawings I have shown three injectors on each side of the chamber C and five injectors across the front of the chamber C.

25 indicates a slag-dam in the chamber C; 26, slag-doors; 27, door through which the metal may be drawn off; 28, friable hearth in the chamber C.

Situated at the upper end of the chamber A is a hopper 29, and immediately in front of the hopper is a chimney-flue 30. Located under the hopper is an ore-feed drum 31. 32 is a swinging door in front of the rake 16.

The operation of my device is as follows: The ore is fed into the hopper 29 and falls upon the hearth of the calcining-chamber A. Within the calcining-chamber A the ore is subjected to a gradually-increasing temperature as it moves down the chamber. In order to insure the movement of the ore down the chamber A and into the reducing-chamber B, the rake 16 is reciprocated through the ore. The ore in passing through the chamber A is calcined and parts with its moisture, as well, in the case of sulfur ores, with a portion of the sulfur. When the ore is delivered into the chamber B, it is subjected to a much higher temperature, which is due partially to the heat from the chamber C passing toward the flue 30 and partially, in the case of sulfur ores, to the combustion of the sulfur in the ore. In this chamber the metal, to a large extent, separates from its slag. The slag, being the lighter, finds its way into the chamber C and is drawn off by the slag-door 26 in front of the dam 25. The metal also moves down with the slag, but, being of greater specific gravity, falls below it, and when delivered into the chamber C flows under the dam 25 and finds its way over and in the mass forming the friable hearth 28.

The hearth 28 may be formed of any suitable material, such as sand or dolomite, as is common in reverberatory furnaces. Preferably, however, I form the hearth with a sand or dolomite bottom and charge over it a high-grade matte, fifty to sixty per cent.

The metal and such portion of the slag as is not drawn off by the slag-door 26 in front of the dam mixes with the matte upon the hearth.

The metal and slag in the chamber C is subjected to an oxidizing-temperature pro-

duced by reason of the hydrocarbon-jets 23 and the air-blasts delivered through the openings 15 in the front of the furnace.

The effect of the treatment in the chamber C is to oxidize out all remaining sulfur or effect a combination between the impurities—for instance, the iron associated with the copper and the slag or flux, which may subsequently be drawn off from the furnace. Finally, the crude metal may be drawn from the chamber C.

I wish it understood that I do not limit myself to the means shown for introducing highly-heated air into the oxidizing-chamber, as other means may be employed.

Having thus described my invention, I claim—

1. A metallurgical furnace, comprising in its construction an inclined calcining-chamber, an inclined reducing-chamber, a horizontal oxidizing-chamber, said chambers connected together at progressively lower levels; means for producing the required atmospheres in said chambers, and means for heating the air fed to the oxidizing-chamber, said means consisting of chambers located over and under the oxidizing and reducing chambers.

2. A metallurgical furnace, comprising in its construction an inclined calcining-chamber, an inclined reducing-chamber, a horizontal oxidizing-chamber, said chambers connected together at progressively lower levels, means for producing the required atmospheres in said chambers, and a continuous roof for said chambers having channels therein through which cooling-bodies may be transmitted.

3. A metallurgical furnace, comprising in its construction an inclined calcining-chamber, an inclined reducing-chamber, a horizontal oxidizing-chamber, said chambers connected together at progressively lower levels, a roof for said chambers having channels therein through which cooling-bodies may be transmitted; and an air-heating chamber having a portion of its length situated above the roof of the oxidizing and reducing chambers.

4. A metallurgical furnace, comprising in its construction an oxidizing-chamber, an air-heating chamber, a series of hydrocarbon-burners arranged in front of the oxidizing-chamber and discharging into said chamber, and means for drawing the air from the air-heating chamber and introducing it into the oxidizing-chamber under the hydrocarbon-burners.

5. A metallurgical furnace, comprising in its construction an oxidizing-chamber, a series of hydrocarbon-burners arranged to discharge into the interior of the chamber from opposite sides, a series of hydrocarbon-burners arranged to discharge into the interior of the furnace from the front, and means for introducing hot air under pressure below the hydrocarbon-burners at the front of the furnace.

6. In a metallurgical furnace, the combina-

tion of a reducing-chamber, an oxidizing-chamber, means for producing the required atmospheres in said chambers, an air-heating chamber situated partially over said chambers, and partially under said chambers, and connected by a vertical flue, said air-heating chamber open to the atmosphere at one end, and means located therein for creating a movement of the air toward the interior of the oxidizing-chamber.

7. A metallurgical furnace, comprising in its construction a reducing-chamber, an oxidizing-chamber, said chambers connected together, means for producing the required atmospheres in said chambers, a heating-chamber provided with flues situated over and un-

der the reducing and oxidizing chambers and which follow the contour of the roof and hearth of said chambers; a vertical connecting-flue, a vertical flue in front of the oxidizing-chamber having discharge-orifices communicating with the interior of the oxidizing-chamber, and air-propelling means situated in the flue under the chambers and at the forward end of that portion of the flue under the oxidizing-chamber.

In testimony whereof I affix my signature in the presence of two witnesses.

MARTIN PRIOR BOSS.
